SPORT SHOE

William J. Cohen, Boston, Mass., assignor to

Filed Aug. 21, 1972, Ser. No. 282,050

Term of patent 14 years

Int. Cl. D2—04

U.S. Cl. D2—310

Fig. 2

Fig. 4

FIG. 1 is a side perspective view of a sport shoe adapted to be worn on the right foot showing my new design;

FIG. 2 is a top plan view;

FIG. 3 is a side perspective view of the left sport shoe with the ornamentation thereon modified as shown; and

FIG. 4 is a top plan view.

I claim:

The ornamental design for a sport shoe, substantially as shown and described.
